ABSTRACT

A nonlinear circuit consisting of first and second circuits. The first circuit comprises a power source, an inductance element L_1 and a capacitance element C connected in an oscillating arrangement. The second closed circuit comprises said capacitance element, an inductance element L_2 and a voltage responsive switching element. The second closed circuit is controlled for operation under either oscillating or nonoscillating condition depending on the necessary output voltage.

NONLINEAR CIRCUIT DEVICE

BACKGROUND

1. Field of the Invention

This invention relates to nonlinear circuits and more particularly to structurally simple high-voltage generators capable of delivering very large amplitude voltages and instantaneous power.

2. Description of the Prior Art

It is generally known that a very large amplitude voltage and instantaneous power are required to turn on a discharge lamp or to ignite an internal-combustion engine or the like. For this purpose, stepup transformers have been used. In cathode-ray tubes, a blocking oscillator circuit is used, providing a special waveform such as a saw-tooth wave. A variety of this type of power converter circuit is now available for use according to requirements.

SUMMARY OF THE INVENTION

An object of this invention is to provide an improved nonlinear circuit consisting of a first closed circuit comprising at least one power source and further comprising an inductor and a capacitor, which are arranged for a certain oscillating condition; and a second closed circuit comprising said capacitor, an inductor and a voltage-responsive switch.

It has been discovered, as one aspect of the invention, that the above-mentioned nonlinear circuit can be used as an oscillator circuit or a pulse generator circuit depending on whether the second closed circuit is in oscillation or nonoscillation condition. The oscillating condition results when

$$\frac{R_1^2}{4L_1^2} - \frac{1}{CL_1} < 0$$

where the first closed circuit has a capacitance C , inductance L_1 and resistance R_1 including the inherent resistance component thereof. With this arrangement, it is found that a markedly amplified output voltage can be obtained.

It will not be assumed that the second closed circuit has a capacitance C , inductance L_2 and resistance R_2 including the inherent resistance component thereof, wherein the capacitor is same as in the first closed circuit, and

$$\frac{R_2^2}{4L_2^2} - \frac{1}{CL_2} < 0$$

preferably near resonance condition as expressed by $2\pi f_2 L_2 \approx 1/2\pi f_2 C$ (where f_2 is frequency of the second closed circuit), and that the inductance L_1 is larger than L_2 , and the second closed circuit is set for oscillating condition. By this arrangement, an oscillator circuit is formed. This circuit is capable of amplifying a given input voltage to a markedly large output oscillating voltage, which is delivered across the capacitance C at the output terminals. This output voltage can be effectively used for any circuit which requires a high voltage to turn on a discharge lamp or to ignite an internal-combustion engine or the like, or for the saw-tooth wave generator for a CRT. In other words, the invention makes it possible to form starting circuits or oscillator circuits effectively with very simple arrangements.

When the second closed circuit is set for nonoscillating condition where

$$\frac{R_2^2}{4L_2^2} - \frac{1}{CL_2} > 0$$

and $L_1 \gg L_2$ (the references denote the same circuit elements as previously), then a pulse generator circuit is formed whereby a pulse voltage whose peak value is very high can be obtained across the output terminals. This pulse voltage can be effectively utilized for the turning on of a discharge lamp or the like. This simplified nonoscillating circuit is effectively applicable to all kinds of devices which need pulse voltage.

In connection with the above-mentioned circuit, generally, the value of the first inductance element L_1 of the first closed circuit is determined to be larger than that of the second in-

ductance element L_2 . Therefore the influence of the oscillating condition due to variation of values in the second inductance element L_2 is substantially negligible on the first closed circuit.

Brief Description of the Drawings

FIG. 1 is a circuit diagram showing the principles of the invention;

FIGS. 2(a)-(c) are equivalent circuit diagrams of FIG. 1 showing the operation of the invention;

FIG. 3 is a waveform diagram showing an output voltage appearing across the capacitor in FIG. 1;

FIG. 4 is a circuit diagram showing a nonlinear circuit device embodying this invention;

FIG. 5 is a circuit diagram showing an arrangement wherein the first and second closed circuits of FIG. 4 are electromagnetically coupled with each other to permit controlling the oscillator energy;

FIG. 6 is a circuit diagram showing an arrangement wherein the output voltage can be derived in a trapezoidal waveform;

FIG. 7 is a circuit diagram showing a multistage arrangement; and

FIG. 8 is a diagram showing a circuit for stepping up the output voltage, this circuit being suited for pulse generation according to the invention.

DETAILED DESCRIPTION

FIG. 1 shows a circuit consisting of a first closed circuit which comprises a DC source 1, a power switch 2, a first inductor 3 and a capacitor 4; and a second closed circuit which comprises said capacitor 4, a second inductor 5 and a voltage responsive switch 6 which is rendered conductive by a specific voltage.

The first closed circuit is set for an oscillating condition by determining the values of the circuit elements L_1 and C . The constants of the circuit elements of the second closed circuit are determined to set this circuit for an oscillating or nonoscillating condition depending on the uses which will be described later.

The operation of the second closed circuit under the oscillating condition will be specifically described below by referring to the circuit diagram and other circuit diagrams showing embodiments of the invention.

The operation of the logical circuit of FIG. 1 under the oscillating condition will next be explained in operating sequence:

1. First Charging Process

In FIG. 1, when the power switch 2 of power source 1 for DC voltage E is closed, this state 1 is expressed equivalently by the circuit in FIG. 2(a) since the voltage responsive switch 6 is in the nonconducting state at this moment. In this equivalent circuit, when the power switch 2 is assumed to be closed at time $t=0$, the current i_1 and the voltage across the capacitor 4, namely the output voltage e_c varying as lapse of time are expressed by the following equations:

$$i_1 = \frac{E}{\sqrt{L_1 C}} \sin \frac{1}{\sqrt{L_1 C}} t \quad (1)$$

$$e_c = \left(1 - \cos \frac{1}{\sqrt{L_1 C}} t \right) \leq 2E \quad (2)$$

In other words, the output voltage e_c becomes twice the power source voltage E at time $t=\pi\sqrt{L_1 C}$. Practically, the operating breakdown voltage V_{bo} of the voltage responsive switch 6 becomes smaller than the output voltage e_c . Because there is a phase difference of $\pi/2$ between the voltage and current, the nonconducting state is maintained until the time t after the power switch 2 has been closed. This operation is shown by the range between 0 and I of the characteristics curved in FIG.

3, for example, in case that the breakdown voltage V_{bo} of the voltage responsive switch is equal to $2E$.

II. First Discharging Process

When the value of the output voltage e_c approaches its maximum point I, it becomes possible for the inductor 5 of the second closed circuit to pass a lagging current. The capacitor 4 starts discharging its charge into the second closed circuit. Since the current i_1 flowing in the first closed circuit at the instant of discharge is zero, the second closed circuit operates independently. Under this condition, the logical circuit of FIG. 1 is expressed by the equivalent circuit in FIG. 2(b). In this equivalent circuit, when the time at which the voltage responsive switch 6 turns on is assumed $t=0$, the current i_2 and the voltage e_c across the capacitor 4 varying as lapse of time are expressed by the following equations:

$$i_2 = \frac{2E}{\sqrt{\frac{L_2}{C}}} \sin \frac{1}{\sqrt{L_2 C}} t \quad (3)$$

$$e_c = 2E \cos \frac{1}{\sqrt{L_2 C}} t - 2E \quad (4)$$

wherein e_c is the maximum value of output voltage e_c .

The polarity of e_c is reversed at time $t = \pi \sqrt{L_2 C}$ after the switch 6 has turned on. The current keeps flowing in the circuit until time $t = \pi \sqrt{L_2 C}$ after the switch 6 has been closed. When the output voltage becomes negatively twice the power source voltage E (namely $e_c = -2E$), the current i_2 becomes zero, and it becomes impossible for the voltage responsive switch 6 to maintain its holding current. This makes the switch 6 nonconducting. This operation is shown by the range between I and II of the output voltage characteristic curve in FIG. 3.

III. Second Charging Process

When the voltage responsive switch 6 becomes nonconducting under the condition where the polarity of the voltage e_c across the capacitor 4 is reversed, the circuit of FIG. 1 is expressed by the equivalent circuit in FIG. 2(c). The voltage ($e_c = -2E$) across the capacitor 4 is added to the power source voltage E , and the equivalent power source voltage will be increased to $3E$. In the same way, the power source voltage is added to itself in succession. Therefore, when the number of a charge (i.e., whether it is the first or second charge or same subsequent charge) is assumed n , the voltage across the capacitor e_c is expressed by

$$e_c \leq E(n+1) \quad (5)$$

This operation is shown by the range between II and III of the e_c characteristic curves in FIG. 3.

A series of the above operations is repeated and, theoretically, the amplitude of the oscillation grows infinitely. The oscillating period is determined by $L_1 C$ when the voltage is in the increasing turn, or by $L_2 C$ when the voltage is in the reversing turn.

IV. Function of Inductance L_2

It is believed that the amplitude voltage phenomenon is achieved by using a particular inductance element L_2 . Though the breakdown voltage V_{bo} of the voltage responsive switch 6 is selected as equal to or smaller than the maximum value of the output voltage e_c , (the $2E$ of equation (2) for the first charging process), and as also the inductance voltage e_1 appearing between the terminals of the inductance element L_2 is substantially zero in the first charging process, the polarity reversion of e_c is caused by the second charging process and before the reachable maximum value $2E$ expressed in the equation (2) is achieved. When the coil for L_2 is made with a core of ferrite material to form proper stray capacitance, the terminal voltage e_1 of the inductance element L_2 does not respond as $-L_2 \frac{di_2}{dt}$ during the switching-off state.

Thus, at a time after the current i_2 equals zero, the voltage e_1 having a back swing characteristic remains. If the variation of this characteristic is nearly equal to the variation of the equation (2), the difference voltage V_s between e_c and e_1 , which is

applied to the voltage responsive switch 6, requires a considerably long time to reach V_{bo} . Regardless of this fact, e_c is developed by the characteristic of e_1 . When V_s is equal to V_{bo} , the second closed circuit having high operational quality Q_2 is operated. The current i_2 at a given moment will be developed by repeating discharge. Thereby the developed current i_2 reduces the value of the nonlinear inductance L_2 and causes securing the voltage e_c for stable oscillation.

Practically, however, the output voltage e_c is limited to a certain definite value since the inductor, connecting lines and so forth have resistance components.

An embodiment of the invention in which the second closed circuit is in the oscillating condition will next be explained below with reference to FIG. 4.

FIG. 4 shows a circuit embodying this invention. This circuit consists of a first closed circuit comprising a DC source 1, a first inductor 3, a capacitor 4 and a resistor 7; and a second closed circuit comprising said capacitor 4, a second inductor 5, a voltage responsive switch 6 and a resistor 8. In this circuit, an AC power source may be used instead of said DC source for the first closed circuit.

It is preferable that ferrite magnetic material which has a small inductance loss and ferrimagnetism be used for the inductor 5, and that a static solid-state switch such as a thyristor be used for the voltage responsive switch of the second closed circuit.

The constants of the circuit elements are indicated by C for the capacitor 4, L_1 and L_2 for the first and second inductances 3 and 5 respectively, R_1 for resistance component in the first closed circuit including the resistance element 7 and R_2 for resistance component in the second closed circuit including the resistance element 8.

When the internal resistance of the inductor 3 is not sufficient for the resistance R_1 , a further resistance element is additionally used. Such external resistance element is the resistance element 7. Similarly, an external resistance element 8 may be added to the internal resistance of the inductor 5 to obtain reasonable resistance value R_2 for the second closed circuit. However, this external resistance element 8 is not always necessary for the second closed circuit. This is because, to obtain a high-voltage generator device, the operational quality Q_2 of the second closed circuit must be better than that Q_1 of the first closed circuit.

The oscillating and turn-on conditions in the circuit of FIG. 4 and the oscillating period and output voltage available from the second closed circuit will next be described below:

I. Oscillating Condition

When the first and second closed circuits are both set for the oscillating condition, the following inequalities are established:

$$\frac{R_1^2}{4L_1^2} - \frac{1}{CL_1} < 0 \quad (6)$$

$$\frac{R_2^2}{4L_2^2} - \frac{1}{CL_2} < 0 \quad (7)$$

60

The following relationship is determined in order not to delay the reversing process following the amplifying process:

$$L_1 > L_2 \quad (8)$$

65 The best condition for oscillation is in the resonance of the second closed circuit, that is $2\pi f_2 L_2 = 1/2\pi f_2 C$, wherein f_2 is a frequency of the second closed circuit.

II. Turn-on Condition

It is statically sufficient to effect turn on that the relationship between the power source voltage E and the operating voltage V_{bo} of the voltage responsive switch be determined as follows:

$$E \approx V_{bo} \quad (9)$$

70 However, even if V_{bo} is larger than E due to transient phenomenon, turnon can be realized kinetically by the use of

power switching. For example, when $L_1 \gg L_2$, the following condition must be satisfied:

$$V_{bo} \leq E \left\{ 1 + \epsilon - \frac{R_1}{2} \sqrt{\frac{L_1}{C}} \cdot \pi \sin \phi \right\} \quad (10)$$

where

$$\phi = \tan^{-1} \left(\frac{2}{R_1} \sqrt{\frac{C}{L}} \right)$$

III. Oscillating Period

Generally, the output voltage of the oscillating period is a uniform saw-tooth wave. The oscillating period T is expressed by the following equation:

$$T = T_1 + T_2 \quad (11)$$

In the actual circuit device, the resistance value R_2 is small and therefore T_2 is derived from the equation (3). Then,

$$T_2 = 2\pi \sqrt{L_2 C} \quad (12)$$

while, T_1 is so complicated that it cannot be simply expressed. Based on the experimental result, however, the following relationship is obtained:

$$T_1 \doteq f(E, R_1, L_2, C) \quad (13)$$

To be more concrete, the following experimental equation is found by rough approximation:

$$T_1 \doteq K_1 \frac{\sqrt{R_1 L_2 C}}{K_2 + E} \quad (14)$$

where K_1 and K_2 : constant

In any case, it is evident that this oscillating period is greatly different from that in the conventional saw-tooth wave oscillator (relaxation oscillator) of LC oscillator. In case the oscillating frequency is smaller than 100 kHz., T is nearly equal to T_1 .

V. Output Voltage

The output voltage is also so complicated that it cannot be expressed by a simple equation. Experimentally, the output voltage e_c was found to be about 50 times the power source voltage.

The maximum value of the output voltage is expressed substantially as;

$$e_{cmax} = K_3 \sqrt{\frac{L_2}{C R_1}} E + K_4$$

where K_3 and K_4 : constant

Why so high an output voltage can be obtained is due to the fact that the discharge sustaining period T_2 of the second closed circuit can be made much shorter than the charge sustaining period T_1 of the first closed circuit under the condition wherein operational quality Q_2 of the second closed circuit is very high and the second closed circuit is set at nearly resonance condition. As a result, the relationship $i_1 < i_2$ is instantaneously established. Such voltage is far greater than the operating voltage V_{bo} of the switching element 6 of the thyristor. In this operation, the switching element 6 will not reach "breakover" since there is a phase angle difference between the output voltage (condenser voltage) and the oscillating current in the second closed circuit. In other words, the voltage is increased during the time corresponding to this phase difference. Seen from the output terminal of the second closed circuit, for example, the voltage applied to the switching element 6 is blocked by the inductor 5 for a certain period of time.

It is believed that there is a certain characteristic of the particular inductance element 5, which is of a nonlinear type, which produces a developed oscillating voltage. More particularly, when the magnetic flux of the core of inductor 5 is in saturated state during the conducting state of the voltage responsive switching element 6, due to the current i_2 having a relatively high peak and flowing into the second closed circuit (due to the high operational quality Q_2 of the second closed circuit) when the switching element 6 is opened, the inductor 5 permits inducing a relatively big backswing voltage in connection with the distributed stray-capacitance factor thereof. This backswing voltage blocks the developed condenser out-

put voltage v_c , which will be applied to the switching element 6 through the inductor 6. Thus, the terminal voltage e_1 of the inductor 5 and the terminal voltage e_c of the capacitor 4 cancel each other so that the output voltage e_c may develop to so high a value. Also, energy of the capacitor 4 may be stored proportionally to the square of the maximum value of output voltage v_c .

The output voltage takes a waveform such as a saw-tooth round saw-tooth wave, triangular wave, round triangular wave, or the like depending on the velocity of variation in the energy stored in or released from the inductor. The frequency of the output voltage is determined by the turnoff time inherent in the thyristor which in a component such as a silicon symmetrical switching element is experimentally determined to be between 5 kHz. and 10 MHz.

According to the results of experiments with the circuit shown in FIG. 4, an output voltage e_c of 360 v. was obtained from a source voltage of 60 v., wherein each of the elements had values as follows:

$$R_1 = 69.5 \Omega, R_2 = \text{Negligible as a few ohms}, C = 0.03 \mu F, Q_2 = (R_2) \sqrt{(L_2/C)} = 100, L_1 = 565 \text{ mh. } L_2 = 79 \text{ mh.} \text{ (measured by the bridge method at 1 kHz. and } V_{bo} = 60 \text{ v.);}$$

A Mn-Zn ferrite core was used for L_1 and L_2 , and the voltage responsive switch was a symmetrical switching element consisting of an NPNPN five-layer diode.

Instead of a DC source, an AC power source may be used. When an AC of commercial frequency is used, this frequency is very low compared with the oscillating frequency. Therefore the oscillator will have a varying frequency due to variation in the instantaneous value of the power source voltage according to the approximate expression of the following equation

$$T_1 = \frac{\sqrt{R_1 L_2 C}}{K_2 + K_1 Z_1 I_1}$$

where I_1 and Z_1 are the current and impedance of the first closed circuit. Assume that the value of L_2 is suitably determined as, for example, such that the magnetic body is saturated by the current i_2 , and its characteristic is varied along a reducing curve, the envelope of the oscillating voltage can be controlled.

In the succeeding embodiments, an AC power source 1' is used. Instead of AC power source, the DC source in FIG. 4 may be employed. The same components as in FIG. 4 are indicated by common references. The resistors 7 and 8 are omitted.

FIG. 5 shows another embodiment of the invention, wherein an inductor 9 having a primary coil 10 and a secondary coil 11 which are electromagnetically coupled with each other is disposed in the second closed circuit. The two coils of the inductor 9 are connected with each other either magnetizingly or demagnetizingly, and their inductances are determined so as to be adequately varied by i_2 . By this arrangement, the inductor 9 is fully saturated ($L_2 = 0$) at an arbitrary phase angle of half-cycle of the power source voltage so that the inductance is zero and thus the oscillation can be stopped and the oscillating energy can be controlled. In this embodiment, the first inductor 3 may be omitted, because inductance L_1 is provided by the coil 10.

FIG. 6 shows another embodiment of the invention, wherein a very small inductor 12 is connected in series with the capacitor 4. In this circuit, the energy stored in the inductor 12 during flow of the discharge current is released in the charging process. As a result, the output voltage across the capacitor 4 takes a trapezoidal waveform. In this manner, the oscillating waveform can be controlled.

FIG. 7 shows still another embodiment of the invention, wherein a capacitor 4', an inductor 5' and a voltage responsive switch 6' are intermediately connected thereto whereby a multistage oscillator is realized. In this circuit, the inductor 5' is operated as the inductance of the second closed circuit in the first stage and also as the inductance of the first closed cir-

cuit on the second stage. The output voltage of the first stage is increased by operating the inductor 5' as a step-up transformer. The stepped up voltage can be applied to the second stage circuit. Similarly, the number of stages may be increased to more than three to obtain an oscillating output of special waveform.

FIG. 8 shows another embodiment of the invention. In this circuit, the oscillating voltage is increased by the turn ratio between the primary and secondary windings of the transformer 12 and the capacitor charging and discharging current is used to excite the core of the transformer 12 in the same direction and thus the envelope of the output voltage approaches a rectangular waveform.

When the second closed circuit is set for the nonoscillating condition, the discharge current varies in the form of an exponential function, and the output voltage takes an impulse waveform. When this operation is considered in connection with the circuit in FIG. 4, the first charging process is the same as in the oscillating condition, but the first discharging process goes in the following manner: Namely, the relationship between the two inductances is $L_1 \gg L_2$, and the second closed circuit operates independently. The current i_2 is in impulse form and can be expressed by the following equation:

$$i_2 = \frac{E}{2\beta L_2} \left\{ e^{-(\gamma-\beta)t} - e^{-(\gamma+\beta)t} \right\} \quad (15)$$

where

$$\gamma = \frac{R_2}{2L_2}, \quad \beta = \sqrt{\frac{R_2^2}{4L_2^2} - \frac{1}{CL_2}}$$

By this impulse current, the maximum terminal voltage e_{cmax} across the capacitor 4 will be

$$e_{cmax} = \frac{E}{2\beta L_2 C} \frac{e^{-(\gamma+\beta)t} - e^{-(\gamma-\beta)t}}{\gamma + \beta - \gamma - \beta} \quad (16)$$

In this circuit, such oscillating current as flows under the oscillating condition does not flow and the voltage responsive switch 6 maintains its conducting state. Thus, the current from the power source flows through the inductors 3 and 5. In this case, if the power source is AC said impulse voltage is produced when the polarity of the flowing current is reversed. When the current is decreased to zero, the saturated magnetic flux density B_s is varied but is maintained due to the square hysteresis characteristic of the core which has a curve maintaining a substantially saturated magnetic flux condition until the reversing of current polarity. However, when the current i_1 is reversed, the capacitor 4 charges and then discharges. The discharge current i_2 of the capacitor 4 produces the magnetic flux within the core of the inductor 5 in reversed direction relative to the above-mentioned flux density B_s , so the magnetic flux density $+B_s$ is abruptly changed to the reverse magnetic flux density $-B_s$. This abrupt variation of the magnetic flux causes a large inductance L in the inductor 5, and thereby a high pulse voltage occurs in the second closed circuit. This impulse voltage is unidirectional and there is no possibility of effecting a voltage inversion amplifying process as in the foregoing oscillating condition.

I. Impulse Voltage Generating Condition

In order to substantially isolate the first closed circuit from the impulse current, the relationship between the two inductances must be

$$L_1 \gg L_2 \quad (17)$$

Also, the following relationship must be established since the first closed circuit is set for the oscillating condition, and the second closed circuit for the nonoscillating condition:

$$\frac{R_1^2}{4L_1^2} - \frac{1}{CL_1} < 0 \quad (18)$$

$$\frac{R_2^2}{4L_2^2} - \frac{1}{CL_2} > 0 \quad (19)$$

In this circuit, turn-on operation is performed under the same conditions as in the foregoing oscillating condition.

According to the embodiment, for example, of FIG. 8, this 5 nonlinear circuit is suited for pulse generation by setting the second closed circuit for the nonoscillating condition. Practically, the value of inductance L_2 is determined to be smaller than that in the oscillating condition. In this circuit, one end of the capacitor 4 is connected to an intermediate tap "a" of the inductor 12 and thus the impulse voltage is stepped up. In one 10 experimental circuit device, a magnetic material having a square-loop hysteresis curve is used for the core of the induction 12 in order to increase the flux variation level from the saturation flux level to the reversely characteristic flux saturation level. The value of the inductance ranges in the order of from microhenries to megahenries, and thus an impulse wave 15 output voltage e of more than 10,000 v. is obtained with a 200 v. power source voltage.

According to this embodiment, the width of the impulse 20 voltage is about 0.1 to several tens of microsecond. When the circuit of this invention is set for pulse generation, inductor 12 as inductance L_2 is composed of the square-loop hysteresis magnetic materials such as 50 percent nickel-iron alloy produced as "Sendelta" by Tohoku Metal Industries, Ltd. in 25 Japan.

As has been described above, the invention makes it possible to obtain a large amplitude output voltage through very simple arrangement. The circuit device of this invention can therefore be widely applied to discharge lamp turnon devices 30 and similar systems. The impulse wave voltage generator circuit of this invention is particularly useful when applied to turnon devices for internal-combustion engines, and the output voltage of the saw-tooth wave oscillator circuit can be effectively used for the sweep circuits of static deflection cathode-ray tubes. Also, according to the invention, the trapezoidal wave oscillating output voltage has a large oscillating energy 35 and therefore this output can be effectively used for the purpose of biasing the magnetic body. Because a voltage responsive switching element having a sufficiently large breakover current capacity is employed in combination with a serially connected inductor, the circuit reliability is greatly increased.

The invention, because of its high practicality as evident 40 from the foregoing description, can be put to use in many ways and in numerous fields, particularly when combined with a 45 suitable waveform modifier.

We claim:

1. A nonlinear circuit device consisting of a first closed circuit which comprises a power source, a capacitance element and a first inductance element in interconnected relation; and 50 a second closed circuit which comprises a voltage responsive switching element, a second inductance element and said capacitance element of the first closed circuit in interconnected relation, the second closed circuit being coupled with said first closed circuit by said capacitance element; said first inductance element and capacitance element having values 55 putting the first closed circuit in oscillating condition; said circuit device being in the form of an oscillator circuit and said elements having values to satisfy the following conditions:

$$60 \quad \frac{R_1^2}{4L_1^2} - \frac{1}{CL_1} < 0$$

$$65 \quad (1) \quad \frac{R_2^2}{4L_2^2} - \frac{1}{CL_2} < 0$$

$$65 \quad (2) \quad \frac{R_2^2}{4L_2^2} - \frac{1}{CL_2} < 0$$

$$65 \quad (3) \quad L_1 > L_2$$

where

70 L_1 : inductance value of the first inductance element
 L_2 : inductance value of the second inductance element
 C : capacitance value of the capacitance element
 R_1 : resistance value of the first closed circuit
 R_2 : resistance value of the second closed circuit
 ω : $2\pi f_2$, and f_2 is a frequency of the second closed circuit.

2. A nonlinear circuit device as claimed in claim 1, wherein the second inductance element includes a core of ferrite magnetic material.

3. A nonlinear circuit device consisting of a first closed circuit which comprises a power source, a capacitance element and a first inductance element in interconnected relation; and a second closed circuit which comprises a voltage responsive switching element, a second inductance element and said capacitance element of the first closed circuit in interconnected relation, the second closed circuit being coupled with said first closed circuit by said capacitance element; said first inductance element and capacitance element having values putting the first closed circuit in oscillating condition; said circuit device being in the form of a pulse generator circuit and said elements having values to satisfy the following conditions:

$$(1) \quad \frac{R_1^2}{4L_1^2} - \frac{1}{CL_1} < 0$$

$$(2) \quad \frac{R_2^2}{4L_2^2} - \frac{1}{CL_2} > 0$$

$$(3) \quad L_1 >> L_2$$

where

L_1 : inductance value of the first inductance element
 L_2 : inductance value of the second inductance element
 C : capacitance value of the capacitance element
 R_1 : resistance value of the first closed circuit
 R_2 : resistance value of the second closed circuit

4. A circuit device as claimed in claim 3, wherein the second inductance element of the second closed circuit includes a core of square-loop hysteresis magnetic material.

5. A nonlinear circuit device consisting of a first closed circuit which comprises a power source, a capacitance element and a first inductance element in interconnected relation; and a second closed circuit which comprises a voltage responsive switching element, a second inductance element and said capacitance element of the first closed circuit in interconnected relation, the second closed circuit being coupled with said first closed circuit by said capacitance element; said first inductance element and capacitance element having values putting the first closed circuit in oscillating condition; the switching element being a thyristor.

6. A device as claimed in claim 1 wherein

$$\omega L_2 \neq 1/\omega C.$$

7. A circuit device as claimed in claim 1 wherein the first and second inductance elements are connected in series with the capacitance element connected to the inductance elements in T relationship therewith.

8. A circuit device as claimed in claim 7 comprising resistances in series with each of said inductance elements.

9. A circuit device as claimed in claim 7 comprising a further inductance element in series with said capacitance ele-

ment and coupled inductively with said second inductance element.

10. A circuit device as claimed in claim 7 comprising a further inductance element in series with said capacitance element.

11. A circuit device as claimed in claim 7 comprising a transformer between said first and second inductance elements and including serially connected coils and a further capacitance element and switching element connected in π relationship with one of said coils.

12. A circuit device as claimed in claim 7 comprising a coil between said inductance elements and constituting with the second inductance element a transformer.

13. A circuit device as claimed in claim 3 wherein the first and second inductance elements are connected in series with the capacitance element connected to the inductance elements in T relationship therewith.

14. A circuit device as claimed in claim 13 comprising resistances in series with each of said inductance elements.

20 15. A circuit device as claimed in claim 13 comprising a further inductance element in series with said capacitance element and coupled inductively with said second inductance element.

16. A circuit device as claimed in claim 13 comprising a further inductance element in series with said capacitance element.

25 17. A circuit device as claimed in claim 13 comprising a transformer between said first and second inductance elements and including serially connected coils and a further capacitance element and switching element connected in π relationship with one of said coils.

18. A circuit device as claimed in claim 13 comprising a coil between said inductance elements and constituting with the second inductance element a transformer.

30 19. A method for controlling a nonlinear circuit wherein first and second inductance elements connected in series with a voltage responsive switching element are further connected in T relationship and in first and second closed loops with a capacitance element which is in parallel relationship with said switching element, said method comprising making the relationship

$$\frac{R_2^2}{4L_2^2} - \frac{1}{CL_2}$$

45 greater or less than zero wherein

R_2 = resistance in the second

L_2 = inductance of the second inductance element

C = the capacitance of the capacitance element

while keeping

$$\frac{R_1^2}{4L_1^2} - \frac{1}{CL_1}$$

50 equal to less than zero wherein

R_1 = resistance in the first loop

L_1 = inductance of the first inductance element.
